UNITED STATES PATENT OFFICE.

LEWIS C. MCADAMS AND GEORGE S. ROBINSON, OF LOS ANGELES, CALIFORNIA; SAID ROBINSON ASSIGNOR TO DAVID CARPENTER, OF LOS ANGELES, CALIFORNIA.

AUTOMATIC DANGER-SIGNAL FOR RAILWAYS.

1,113,455.

Specification of Letters Patent.

Patented Oct. 13, 1914.

Application filed August 14, 1911, Serial No. 644,050. Renewed March 25, 1914. Serial No. 827,052.

To all whom it may concern:

Be it known that we, LEWIS CLARK MCADAMS and GEORGE S. ROBINSON, citizens of the United States, and residents of the city and county of Los Angeles, State of California, have invented certain new and useful Improvements in Automatic Danger-Signals for Railways, of which the following is a specification.

10 Our invention pertains to signals for railways, and it has special reference to danger signals for railway crossings of the class wherein the train itself mechanically operates the signaling device.

15 The object is to provide a simple and efficient signaling mechanism which can be readily attached to tracks at crossings, and when once installed will not get out of order, as will now be set forth in detail.

20 In the accompanying drawing Figure 1 is a side elevation of the track shoe which operates the signaling mechanism. Fig. 2 is a cross section of the rail showing the shoe in position. Fig. 3 is a top view of the shoe. 25 Fig. 4 is a top or plan view of a railway track showing the signal mechanism in position, and Fig. 5 is a side view of the track and signal post.

20 In constructing our invention we provide a shoe which comprises a base member 6, hinged at one end, as at 7, either to the tie 8, or to a suitable base alongside one of the rails 9. The other end of this base member is held in such a position by a bracket 10, that the member has a limited vertical movement, and it is provided with a downwardly-projecting arm 11, to which the operating cable 12 is attached, this cable extending upwardly and over a grooved pulley 13, along side the rail 9.

35 The upper edge of the base number 6 has integral therewith hinge ears 14, to receive the ears 15, of an upper member 16, this upper member having an inclined tread surface 17, which is in such a position that the wheel 18 of the car will engage therewith and thus depress the free end of the two members 6, 16.

40 The tread 17, has one of its ends cut away at an angle, as shown at 19, this cut-away portion being at the free end of the members, and at the end opposite to the inclined portion, so that the wheel in traveling along will gradually depress the members, when

going in one direction, but in traveling the opposite direction the side of the wheel will strike the inclined surface 19, and thus tilt the upper member 16, without depressing their free ends.

45 In order to cause the upper member to normally rest alongside of the rail a pair of flat springs 20, are secured at their lower ends to the base member 6, so that their upper ends bear against the outer surface of the upper member, as shown in Fig. 1.

50 In practice two of these shoes are placed alongside of the track, one on each side of the crossing, and at any desired distance therefrom, each shoe being so disposed that it will be depressed when a car moves in one direction, but will not be depressed when the car moves in the opposite direction as stated.

55 Midway between the cables is a grooved pulley 21, secured to a vertical pivot pin, and at a suitable point out from the railway track at each side is a post 22, having on each side thereof, in line with each edge of the grooved pulley 21, a pulley 23, these latter pulleys being on horizontal pivot pins.

60 At the upper end of each post is a grooved pulley 24, which carries an arm 25, on which is a signal flag, or other means of attraction, and which when in operation is swung down to attract those who are about to cross the track.

65 Instead of employing mechanical means for signaling, a light may be displayed by the same mechanism, or a bell set in motion, or all these adjuncts may be in connection with the signal flag, or semaphore, used on 70 the post.

75 It is obvious that the device may be equipped on a double track as well as on a single track, so that as a train approaches the crossing the signal is displayed before 80 the train arrives at the crossing, and the second shoe beyond the crossing will restore the signal to its normal position.

85 What we claim as new is:—

90 1. In a danger signal, a railway track 100 having alongside one rail thereof a shoe, comprising two horizontal members, the lower member thereof hinged at one end, so that the other end is capable of moving vertically, the upper member having an inclined tread normally above the tread of the rail, and hinged to the lower member on a horizontal line, the elevated end of said up-

per member having a cut-away angle, whereby its upper end may be swung outwardly by the car wheel.

2. In a danger signal, a railway track having alongside one of the rails a shoe, comprising a base member, one end of which is hinged so that its free end has a limited vertical movement, said free end having an arm to which the operative cable is attached, 10 an upper member hinged to the lower member, so as to swing away from the rail, and provided with an inclined tread normally above the tread of the rail, and with means for coöperating with the wheel to swing the upper member away from the rail, and a signal or semaphore connected up with and operated by the said shoe.

3. In a danger signal, a railway track having alongside one rail thereof, a horizontally disposed shoe, comprising two members,

the lower member hinged at one end, and the other free end secured behind a bracket so that it has a limited vertical movement, an upper member hinged to said lower member on a horizontal line, provided with an inclined top or tread, an angled or cut-away portion at one end of said upper member to provide a contact surface for the side of the car wheel, and a pair of springs secured to the lower member and bearing against the upper member to normally keep the said member in a vertical position.

Signed at the city and county of Los Angeles, State of California, this 8th day of August, 1911, in the presence of witnesses.

LEWIS C. MCADAMS.
GEORGE S. ROBINSON.
